UNITED STATES PATENT OFFICE.

EDWARD F. WILKINSON, JR., OF GRAMERCY, LOUISIANA.

VALVE-LIFTER.

1,331,305.

Specification of Letters Patent. Patented Feb. 17, 1920.

Application filed June 12, 1919. Serial No. 303,580.

To all whom it may concern:

Be it known that I, EDWARD F. WILKINSON, Jr., a citizen of the United States, residing at Gramercy, in the parish of St. James and State of Louisiana, have invented certain new and useful Improvements in Valve-Lifters; and I do hereby declare the following to be a full, clear, and exact description of the invention, such as will enable others skilled in the art to which it appertains to make and use the same.

My invention relates to improvements in devices for withdrawing the various parts of valve mechanisms from their seated positions; and it relates more especially to the removal of valves and their seats from internal combustion engines, such as automobile engines, or the like, and it is the purpose of the invention to raise these parts quickly and effectively when desired, either for purposes of cleaning or repair.

Such parts are apt to stick very hard in their seats, and to effect their removal considerable power has to be applied in a convenient way. Such results are procured by the hereinafter described device.

Reference is had to the accompanying drawings, in which like parts are indicated by similar reference symbols throughout the several views, and in which:—

Figure 1 is a sectional elevation through the valve casing and its contiguous parts, the valve being shown in elevation and parts of the valve lifter being shown in section, the valve casing being shown in the fixed position; and

Fig. 2 is a similar view, but showing the parts of the valve casing and valve in elevation, and also showing the lifter in elevation, but with the valve casing lifted and the lifter in the closed position.

A represents the cylinder casing bored as at *a* to receive the valve casing B, which is provided with the valve seat *b* and the central sleeve *b'* adapted to receive the stem C' of the valve C. This valve casing is held in place by the screw collar B' and the packing ring B².

D represents the valve stem head, which is cup-shaped as shown in Fig. 1, and into this head the pin E projects from the valve stem.

F represents the valve spring which bears

at one end on the valve stem head, and at the other end on an annular plate or washer G mounted above the valve casing B.

55

So far all of the parts are of standard make and are merely illustrative of the action of the apparatus, and these parts may be changed without in any way affecting the invention itself, which will now be described.

60

The lifter comprises the main frame or yoke H, provided with legs *h* to which are adjustably attached the shoes H', as by the pins *i* passing through the holes *h^o* in the legs *h* and in the shoes H'. This frame is perforated, as at *h'*, to receive the reciprocating draw-bar J to which are pivoted the claws K and K'. The claw K is shorter than the claw K', but is long enough to pass beneath the flange *d* of the stem head D, and to engage the first coil of the spring F.

65

The claw K' is made somewhat longer so as to engage the two upper coils of the spring F, so that these upper coils of the spring will afford a wide bearing in the operation of lifting, and will ordinarily obviate any danger of the claws pulling through or bending the flange *d* of the stem head.

70

The draw-bar J is reciprocated by a toggle joint arrangement comprising two bell crank levers M and M', hinged to the head of the draw-bar J as at *m*, and having their pivots *m'* connected by the links L and L', respectively, to the main frame H. To the upper arms of the bell crank levers M and M' the hand levers N and N' are pivoted, as at *n*, and these levers are connected together by the link O, and are provided with handles *n'*. The handles are ordinarily thrown to the open position, as shown in Fig. 1, and at the same time the draw-bar J is ordinarily thrown to the lower or initial engaging position as shown in said figure, by means of the coil spring P.

75

In order to operate the device, first remove the rocker arm, not shown, from over the valve to be removed, then unscrew the collar or bushing which holds the valve casing in the cylinder, and after this apply a little kerosene to each valve casing, as the bushing is unscrewed, as this will tend to soak the parts loose; after this place the

100

lifter directly over the valve stem with the legs set firmly on the cylinder, the shoes, of course, being adjusted to the length of the valve stem which is being operated upon; 5 then take a pair pliers and turn the valve until the pin E is on the same angle as the claws K and K'. Then turn the valve spring until the first coil is under the flange d opposite the claw K and press this claw 10 into the spring under the first coil, then press the long claw K' into the spring under the second coil. After the claws K and K' are in engagement beneath the coils of the spring aforesaid, and the legs of the frame 15 in the proper position, squeeze the handles n' together and this will cause the toggle joint arrangement to lift the valve casing free of its seat, and in a position to be conveniently handled by the operator.

20 If the stem head D threatens to bend, remove it and the valve spring and apply a special steel washer beneath the pin E. Any amount of pressure can now be applied, without causing damage, until the valve and 25 the casing have been extracted.

By having the legs of the main frame adjustable, the lifter may be quickly adapted to any ordinary length of valve stem; but it will only be necessary to adjust the legs 30 once for any given automobile, or once for any given types of automobile engines where the valve stems are of substantially the same length.

The herein described device is especially 35 adapted for use with various standard types of automobiles, auto trucks, or the like, and may be readily attached to almost any kind of internal combustion engines in which there is a projecting valve stem.

40 The herein described device is light and cheap, and of such dimensions that it may be carried on any tool box or kit, or may be used at the garage. It operates very quickly and effectively and does not require the use 45 of any additional tools except a wrench to unscrew the collar or bushing B'. Moreover in using the tool there is no danger of bending the valve stems or injuring the springs, or stem heads, or of cracking or 50 breaking the valve casing.

It will be seen that the device operates with a straight pull in the direction of the axis of the valve stem and consequently in the direction of the axis of the casing, and 55 that there is no bending tendency whatsoever.

These and various other advantages of the herein described construction will be obvious to any practical mechanic accustomed 60 to operating devices of this character.

It will be obvious that various modifications might be made in the herein described apparatus and in the construction, combination and arrangement of parts which could 65 be used without departing from the spirit

of my invention; and I do not mean to limit the invention to such details except as particularly pointed out in the claims.

Having thus described my invention what I claim and desire to secure by Letters Pat- 70 ent of the United States is:—

1. Apparatus of the character described comprising a main frame provided with downwardly projecting bearing legs, a draw bar slidably mounted in said frame, gripping means carried by said bar, and a toggle joint arrangement carried by said main frame, and comprising a pair of oppositely disposed bell crank levers each pivoted at its lower end to said draw bar, a pair of 80 hand levers having their lower arms pivoted to the upper arms of the said bell crank levers, and the upper arms of said hand levers terminating in handles, the said hand levers being pivoted together between said 85 upper and lower arms, and links each hinged at one end to said frame and at the other end forming a pivot for the corresponding bell crank lever, substantially as described. 90

2. Apparatus of the character described comprising a main frame provided with downwardly projecting bearing legs, a draw bar slidably mounted in said frame, gripping means carried by said bar, and a toggle joint arrangement carried by said main frame, and comprising a pair of oppositely disposed bell crank levers each pivoted at its lower end to said draw bar, a pair of 95 hand levers having their lower arms pivoted to the upper arms of the said bell crank levers, and the upper arms of said hand levers terminating in handles, the said hand levers being pivoted together between said 100 upper and lower arms, and links each 105 hinged at one end to said frame and at the other end forming a pivot for the corresponding bell crank lever with a coil spring for restoring the said toggle joint mechanism to the initial position, substantially as 110 described.

3. Apparatus of the character described comprising a main frame provided with downwardly projecting adjustable legs, a draw bar slidably mounted in said frame, hinged claws carried by said bar, and a toggle joint arrangement carried by said main frame, and comprising a pair of oppositely disposed bell crank levers each pivoted at its lower end to said draw bar, a pair of 115 hand levers having their lower arms pivoted to the upper arms of the said bell crank levers, and the upper arms of said hand levers terminating in handles, the said hand levers being pivoted together between said 120 upper and lower arms, and links each hinged at one end to said frame and at the other end forming a pivot for the corresponding bell crank lever, substantially as 125 described. 130

4. Apparatus of the character described, comprising a main frame provided with downwardly projecting bearing legs, a draw bar slidably mounted in said frame, claws carried by said bar, and a toggle joint arrangement comprising a pair of bell cranks pivoted at one end to said draw bar, and

having their fulcrums connected to said main frame, with arms pivoted together and connected to the free ends of said bell cranks, with means for forcing said arms apart, substantially as described.

EDWARD F. WILKINSON, JR.
